UNITED STATES PATENT OFFICE.

WALTER E. CAWOOD, SR., OF TOLEDO, OHIO.

EYEGLASS-GUARD.

SPECIFICATION forming part of Letters Patent No. 734,667, dated July 28, 1903.

Application filed March 14, 1903. Serial No. 147,808. (No model.)

To all whom it may concern:

Be it known that I, WALTER E. CAWOOD, Sr., a citizen of the United States, residing at Toledo, in the county of Lucas and State of Ohio, have invented certain new and useful Improvements in Antiseptic Eyeglass Guards or Nose-Pieces; and I do hereby declare the following to be a full, clear, and exact description of the invention, such as will enable others skilled in the art to which it appertains to make and use the same.

This invention relates to eyeglass nose guards, the principal features of my invention relating to an eyeglass guard or nose-piece having a duplex integral bearing-arm, said arm having a lateral movement or resiliency in relation to a rigid supporting-arm. The main arm by reason of its resiliency gently presses the cuticle and muscle of the nose at an oblique angle to the plane of the lens and at about a right angle to the crest of the cartilage-bone, the supporting-arm resting on the side of the same, and serves as a support to the lens, the terminating circular portion of the guard engaging the nose at its narrowest part and transverse to the visual axis of the eye, as illustrated in the accompanying drawings.

The object of my invention is to relieve all unnecessary pressure on the nose and to permit of proper circulation, giving ease and comfort to the wearer. This invention being made in a single integral metallic plate and in one continuous piece is so constructed in its alignment as to bear against the cuticle and muscle of the nose throughout the entire length of the metallic surface of the guard, thus making one continuous point of contact. The duplex arm, which is conjoined at its base by the means of a shoe and disengaged at its terminating end, permits the oculist to shape the main bearing-arm to different angles, as desired, without disturbing the position of the rigid supporting-arm from its relative position to the plane of the lens. Lateral resiliency is also obtained by reason of said construction.

The drawings on file and the accompanying model illustrate and show my invention.

Figure 1 is an elevation of the eyeglass-guard, the same being constructed of hard metal of suitable thickness and resiliency.

The general configuration of the guard consists of lug A, supporting-arm B, duplex arm C, and conjunctional shoe D, lug A adapted to secure the guard to the lens-post F with the usual means. Fig. 2 is a perspective side view of the invention, showing the guard in elevation and as applied, the eye and nose being indicated by dotted lines. Fig. 3 is a perspective rear elevation showing the guard in combination with the ordinary lens-post F and bow-spring I.

Arm B is a continuation of the lug downward, said arm taking an inward then outward curve. Arm C is in conjunction with arm B, the same taking an upward direction, an aperture being formed between arms B and C, said arms conjoined at their base by the means of a shoe D, said arms divergent and inset obliquely in relation to the plane of the lens, the terminating end of arm C extending inward. All of the aforesaid parts being integral are intended to bear directly and come in contact with the flesh of the nose while engaging the same.

Having described my invention, I make claim as follows:

1. An eyeglass-guard adapted to bear directly on the flesh of the nose, consisting of a metallic plate, comprising a lug, a supporting-arm, a conjunctional shoe, and a duplex bearing-arm, all of which bear directly on the flesh of the nose throughout the entire metallic surface of the said described parts making one continuous point of contact.

2. As a new article of manufacture an integral nose-guard for eyeglasses, adapted to bear directly on the flesh of the nose, said guard constructed of metal, consisting approximately of a Y-shaped bearing-plate, the vertical section having a slot or aperture cut through the entire length of the same to the base, whereby the rearward section is capable of independent adjustment, the upper rearward divergent section duplex in its construction, said integral nose-guard provided with a lug having countersunk aperture therein, whereby the guard may be engaged in combination with a bow-spring, lens-holder, stud, and lens, substantially as described.

3. As a new article of manufacture in eyeglasses, the combination of bow-spring, a pair of lenses, studs, and integral nose-guards,

said guards adapted to bear directly on the flesh of the nose, said guards consisting approximately of a Y-shaped bearing-plate, the arms of the same so disposed that when the 5 eyeglass is inserted upon the nose of the wearer the main bearing-arm will engage the cuticle and muscle of the nose at an oblique angle to the plane of the lens, and at about a right angle to the crest of the cartilage-
10 bone, the supporting-arm resting on the side of the same, the terminating portion of the main bearing-arm engaging the nose at the narrowest part transverse to the visual axis of the eye, substantially as herein described.
15 4. As a new article of manufacture in eyeglasses, the combination of a pair of lenses, lens-holders, bow-spring, studs, and integral nose-guards, the nose-guards consisting of a

single metallic plate as depicted, the main bearing-arm having a lateral resiliency or 20 movement in relation to the rigid supporting-arm, said resilient arm being disengaged throughout its lateral sides and terminating end, and engaged at its base or lower end with a conjunctival shoe, substantially as 25 herein described, said guard adapted to bear and touch the cuticle of the nose throughout all of its entire metallic surface, when inserted upon the nose of the wearer.

In testimony whereof I hereunto affix my 30 signature in presence of two witnesses.

WALTER E. CAWOOD, SR.
